Patented June 29, 1920.

Inventor: *Se J. Frigg, D. M. Bent,*
By *D. M. Bent, Attorney.*

UNITED STATES PATENT OFFICE.

SPRIGG BRENT, OF COVINGTON, KENTUCKY.

BURIAL-CASKET HANDLE.

1,345,314.

Specification of Letters Patent. Patented June 29, 1920.

Application filed April 14, 1919. Serial No. 289,835.

To all whom it may concern:

Be it known that I, SPRIGG BRENT, a citizen of the United States, residing at Covington, in the county of Kenton and State of Kentucky, have invented certain new and useful Improvements in Burial-Casket Handles, of which the following is a specification.

My invention relates to burial casket handles, and has for its object the provision of means, especially applicable to casket handles having bars which are substantially square in general cross-section, to afford ease in carrying the casket; further, to provide a relieving shield for the under side of the carrying bar of a casket handle when in laterally extended relation for carrying the casket, to enable the bearers of the casket to obtain firm grip upon the bars relieved of discomfort, pain or injury by the bars to the hands of the bearers; and, further, to provide a relieving shield of the character described which, when the bar is in depending relation, which is the normal relation of the bar, is practically invisible, and does not mar the appearance of the handle on which the relieving shield is employed.

The invention will be further readily understood from the following description and claims, and from the drawings, in which latter:

Figure 1 is a front elevation of my improved device, the bar being in raised or laterally extended relation.

Fig. 2 is a rear elevation of my improved device, the bar being shown in depending relation and part of the arms and the lug being removed.

Fig. 3 is a cross-section of my improved device, taken on the line 3—3 of Fig. 1, showing the arm and bar in laterally extended relation in full lines, and in normal or depending relation in dotted lines.

Fig. 4 is a longitudinal section of my improved device, taken in the plane of the line 4—4 of Fig. 3, the ends of the bar being broken away; and

Fig. 5 is a similar section showing a modification of the securing means.

Fig. 11 represents the lug of the casket handle, which may be of any usual or ordinary construction. The lug is attached to the casket the wall of which is indicated at 12. Arms 13 are pivoted to the lug by means of pivot-pins 14 passing through the respective arms and bearing lips 15 at the respective sides

of each arm. The arms are, at their outer ends, provided with loops 16, which may also be termed straps, each of which has an opening 17 through which the bar 18 of the handle is received.

The bar 18 is shown substantially square in general cross-section, and is provided with longitudinal grooves 19 at the respective walls of the bar adjacent to the corners 20 of the bar, the corners being rounded, this being done in order to relieve the appearance of bulk and giving the bar a pleasing appearance.

The bar is usually formed up out of sheet metal, as clearly shown in the drawings, there usually being a seam 25 in the normal inner wall of the bar. The lug and arms may, if desired, be formed out of sheet metal or out of soft cast metal having reinforcing plates therein, as is usual in this art.

When the handle is in normal position, that is to say, when the casket is not being carried, the arms and the bar are in depending relation, as indicated in dotted lines in Fig. 3. When, however, the casket is being carried, the arms and the bar are in laterally extending relation, with the arms substantially horizontal, as shown in full lines in Fig. 3. The arms and the lug are preferably provided with coacting stops 26, 27, which coact when the arms and bar are in laterally extended relation to limit the upward swinging movement of the arms and bar.

The inner wall or face of the bar when in normal or depending position, becomes the lower wall or face of the bar when the latter is in use or laterally extended relation. The latter is the relation of the parts when the casket is being carried. The casket and the contents thereof are often of great weight and it has been found that the bars of the handles, as usually constructed, are hard for the bearers to hold and often are hurtful to the hands of the bearers, the corners, seam and flatting of the bar bearing with great pressure on the hands of the pallbearers when carrying the casket, and causing pain and difficulty in carrying the casket.

In order to avoid these objections, and to provide a ready means for carrying the casket without pain or difficulty, I provide a relieving shield for the under wall or face of the bar, this under wall or face being the under wall or face when the bar is in later-

ally extended relation and the inner wall or face when the bar is in depending relation. This shield is exemplified at 31, and is preferably struck up from sheet metal, and comprises an outwardly bulged portion 32 which slants toward the bar longitudinally of the shield, toward the respective ends of the shield. The longitudinal edges of the shield are bent upwardly, as flanges, as indicated at 33; with substantial roundings 34 extending longitudinally of the shield, the upwardly bent flanges being received at the respective sides of the bar, when viewed in the laterally extended relation of the latter, the longitudinal flanges of the bar being preferably provided with inturned edges 35, preferably curled to form longitudinal beads or curls 36. The inwardly turned longitudinal edges are received in the respective grooves 19 of said respective sides adjacent to the bottom wall or face of the bar, when viewed in laterally extended relation.

The relieving shield is preferably struck up out of sheet metal and has sufficient resilience, so that the inturned longitudinal edges may be sprung into the grooves, so as to be located in said grooves, the upwardly extending longitudinal flanges of the relieving shield being close to the lower side faces of the corners of the bar, when viewed in the laterally extended relation of the latter. The relieving shield, therefore, when the bar is in depending relation, is practically invisible, and does not in any way mar the appearance of the bar or handle or detract from the design of the same. When, however, the bar is in laterally extended relation for carrying the casket, the relieving shield is in position for direct use and acts to remove the pressure of the corners, flutings, seam and grooves of the lower portion of the bar from the hands of the bearers, and presents all rounded surfaces to the hands and increases the cross-sectional size of the bar between the arms, thereby rendering the carrying of the casket easy and avoiding pain or injury to the hands.

If desired, the relieving shield may be fixed to the handle, accomplished, for instance, by providing the ends of the relieving shield with tongues 38, in the form of extensions, which are received between the under stretches 39 of the respective loops 65 of the arms of the handle and the lower wall of the bar, when the arms and bar are viewed in their laterally extended relations, being clampingly held between said stretches and said bar. The ends of the upwardly extending flanges of the relieving shield preferably form shoulders 40 having abutment against the inner faces of the arms to limit longitudinal shifting between the relieving shield and the bar. If desired, the 65 relieving shield may be secured to the bars

by means of tacks or brads 41, passing through apertures in the respective ends of the relieving shield and the metal wall of the bar into the wooden core 42, with which the bar is usually provided.

The ends of the bar are usually provided with suitable tips 43 of usual or ordinary construction, secured to said ends in any usual or ordinary manner.

Having thus fully described my invention, what I claim as new and desire to secure by Letters Patent, is:

1. In a casket handle, the combination of a bar which is substantially square in general cross-section, and a relieving shield for the under side of the bar when the latter is viewed in laterally extended relation, said relieving shield comprising a downwardly bulging portion and longitudinally extending edge portions received about the lower corners of said bar, and sunk into said bar at the sides of said bar to leave the major portion of the circumference of said bar exposed to view.

2. In a casket handle, the combination of a lug, spaced-apart arms pivoted thereto, a bar which is substantially square in general cross-section, said bar received through the outer ends of said arms, said bar provided with longitudinally extending grooves extending through said arms, and a relieving shield for the under side of said bar when the latter is viewed in laterally extended relation, comprising a downwardly bulging portion and longitudinally extending edge portions received about the lower corners of said bar, said shield covering the lowermost grooves in and the lowermost corners of said bar, the major portion of the circumference of said bar exposed to view.

3. In combination, a casket handle comprising a bar having longitudinal grooves at the respective sides of the bar when the latter is viewed in laterally extended relation, and a resilient sheet metal shield provided with longitudinal inwardly and upwardly extending resilient edge portions resiliently held in said longitudinal grooves and resiliently pressing toward the vertical middle of said bar.

4. In combination, a casket handle comprising a lug, arms pivoted thereto having loops at their outer ends, and a bar which is substantially square in general cross-section, said bar received through said loops, and a relieving shield for the under side of said bar when the latter is viewed in laterally extended relation comprising a downwardly bulging portion and longitudinally extending end tongues at the respective ends of said downwardly bulged portion, and longitudinally extending side edges to leave the major portion of the circumference of said bar exposed, said longitudinally extending end tongues held solely

between the lower stretches of said loops and the lower wall of said bar.

5. In combination, a casket handle comprising a lug, arms pivoted thereto having loops at their outer ends, and a bar having longitudinally extending corners and longitudinally extending grooves, said bar and longitudinally extending corners and grooves received through said loops, and a 10 relieving shield for the under side of said bar when the latter is viewed in laterally extending relation comprising a downwardly bulging portion, longitudinal edge portions provided with inturned curls at the 15 respective sides of said shield presented to-
- ward each other and received in said grooves, the said bar extending above said longitudinal edge portions, and said shield provided with end tongues received between said loops and bar and with shoulders above 20 said tongues coacting with said arms to position said shield.

In testimony whereof, I have hereunto signed my name in the presence of two subscribing witnesses.

SPRIGG BRENT.
